(57) **CLAIM**

The ornamental design for a tablet stand, as shown and described.

DESCRIPTION

FIG. 1 is a perspective view of a tablet stand showing my new design;
FIG. 2 is a front view thereof;
FIG. 3 is a rear view thereof;
FIG. 4 is a left side view thereof;
FIG. 5 is a right side view thereof;

FIG. 6 is a top view thereof;
FIG. 7 is a bottom view thereof;
FIG. 8 is another perspective view thereof;

FIG. 9 is an operational perspective view thereof showing the tablet horizontally supported by the tablet stand; and,

FIG. 10 is another operational perspective view thereof showing the tablet vertically supported by the tablet stand.

The broken lines are shown for illustrative purposes only and form no part of the claimed design.
